UNITED STATES PATENT OFFICE

STEPHEN DE ORLOW, OF DETROIT, MICHIGAN, ASSIGNOR TO TERNSTEDT MANUFACTURING COMPANY, OF DETROIT, MICHIGAN, A CORPORATION OF MICHIGAN.

HOOD LATCH

Application filed August 31, 1931. Serial No. 560,340.

This invention relates to latches and has particular reference to a latch for the hoods of automotive vehicles.

In the past, it has been customary to use a plurality of independent hooks or latches, usually two, to hold down the hood on the chassis frame. These hooks have not been easy to operate and have caused some annoyance and it is the object of the invention to combine the two hooks with a single operating member which is easy to operate and which will firmly hold the hood in its lowered position.

The structure of the invention by which the object is accomplished consists in placing two brackets, one each at the dashboard and at the radiator shell closely adjacent the hood in its lowered position. Secured to the inside of the hood adjacent each bracket is a mounting member or bracket which has pivotally mounted thereon a hook which engages under the bracket when the hood is in lowered position. Each hook has an arm to each of which a link is secured, the links extending toward each other and being connected at their center by a resilient connection. A handle extending without the hood and journaled in the hood panel is rigidly secured to the connection and operates the same to cause the hooks to become engaged with or disengaged from the brackets.

The hook may also be in the form of the end of a coil spring, the spring being coiled about and rigidly secured to the pivot. Where this type of hook is used, the connection between the links need not be a resilient one but they may be interconnected by means of an ordinary link.

Where it is desired to operate the hooks independently, the linkage may be dispensed with and an individual handle journally mounted in the hood adjacent each mounting member.

On the drawings:

Figure 1 shows a side view of a hood of an automotive vehicle showing the application of the invention.

Figure 2 is an enlarged detailed view of the bracket and mounting member, the hood be-

ing removed for purposes of clearer illustration.

Figure 3 is a view of the connection between the links which operate the hooks, the dotted line position showing the other extreme position of the connection.

Figure 4 is a section on the line 4—4 of Figure 2.

Figure 5 is a section on the line 5—5 of Figure 3.

Figure 6 is a section on the line 6—6 of Figure 5.

Figure 7 is an expanded view of the connection between the handle and the connecting member of the links.

Figures 8 and 9 are views of a modification corresponding to Figures 2 and 4, Figure 8 being taken substantially on the line 8—8 of Figure 9.

Figures 10, 11 and 13 are views of the second modification corresponding to Figures 3, 6 and 7.

Figure 12 is a perspective detail view of the pivot or stud on which the hook is mounted.

Figure 14 is a view corresponding to Figure 1 of a second modification showing the hooks with individual handles.

Figure 15 is a sectional detailed view through the hood latch.

Figure 16 is an enlarged detail elevation of the hood latch looking from the inside of the hood.

Figure 17 is an expanded view of the handle in interconnecting parts.

Referring to the drawings, the numeral 2 indicates the hood of an automotive vehicle, 4 the cowl, 6 the radiator shell and 8 the chassis frame. Between the hood 2 and the cowl 4, the usual dashboard 10 is provided.

Secured to the dashboard 10 and to the radiator shell 6 are the brackets 12. The brackets may be of any suitable shape and the portion to receive the end 14 of the hooks 16 is preferably inclined. The hooks 16 are pivoted to a bracket 18 having the ears 20 and 22 through which there pass rivets 24 by means of which the bracket is secured to the hood 2. The bracket has the middle inclined portion 26 provided with an opening for the reception of the pivot or stud 28. The pivot

28 is journally mounted in the bracket and has rigidly secured thereto the hook 16. The peened-over portion 30 and the flats 32 rigidly hold the hook on the pivot 28. A spring 34 has one end 36 bent at an angle and positioned in an opening in the pivot 28 while its other end 38 is hooked about the side of the bracket 18. The intermediary portion is coiled about the stud and is under tension and constantly urges the stud and the hook 16 into engagement with the bracket 12.

The hook 16 has the arm 40 extending above the pivot 28 and has pivotally connected thereto by means of the bolt 42 the link 44 which extends toward the center of the hood as shown in Figure 1. Integral fingers 45 on the bracket 18 limit the movement of the arm 40. The two links 44 meet at the center of the hood as shown in Figures 1 and 20 and are interconnected by means of the resilient connection indicated as a whole at 46. The connection comprises the channel 48 formed of a piece of metal bent to rectangular form and having a portion of its ends bent over as shown at 50 to form stops for the blocks 52. Each link 44 is pivoted at its end to a block 52 by means of a pin 54 and suitable slots 56 are provided in the channel 48 to allow for the swinging movement of the 25 links. The blocks 52 are slidable in the channel and a coil spring 58 is confined in the channel between the blocks and always urges the blocks away from each other.

At the split 60 of the channel 48, tongues 35 62 are bent therefrom which engage in openings 64 in a bracket 66. The bracket 66 has a squared shank portion for the reception of the squared end 68 of a handle 70. A pin 72 secures the squared portion 68 in the squared 40 portion of the bracket 66.

The hood 2 is provided with an opening 73 at its lower center adjacent the meeting point of the links 44. Internally of the hood, there is positioned a reinforcing member 74 and 45 exteriorly of the hood a reinforcing member 76 which have conformable openings 78 which mate with the opening 73 in the hood. The members 74 and 76 are secured together by suitable threaded bolts passing through the openings 80 from the interior of the hood and being screwthreaded in the member 76. The reinforcing member 74 has an integral tongue 82 bent therefrom the purpose of which is to serve as a stop for the swing of the handle 70. The handle 70 passes through the openings 78 and is journalled therein. Adjacent the reinforcing member 74 the handle has mounted thereon the disc 84 which fits over the squared portion 68. The disc has the cut-out portion 86 which fits over the tongue 82. If the disc 84 is rotated in either direction, the shoulders at the end of the cut-out portion 86 will strike the tongue 82 to limit the movement of the handle.

60 65 The operation of the device is as follows:

The locked or latched position of the parts is shown in Figures 1, 2 and 3 in full lines. In the dotted outline in Figures 2 and 3, the unlatched position is shown. By moving the handle from the position shown in Figure 1 70 and turning it to the left, the handle will move the channel 48 and cause the pivot pins 54 to swing the links 44 away from the connection. The links will act on the arms 40 of the hooks to cause them to swing on the pivots 28 and move the hooks 16 away from the brackets 12, or to the dotted line position shown in Figure 2. The hood may now be raised by lifting upward on the handle 70. When the hood is lowered, the handle is swung to the right to again return the parts to the positions shown in Figures 2 and 3. In the position shown in Figure 3, it will be noted that the pins 54 are slightly overcentered with reference to the axis of 85 swing of the handle 70 so that there will be no tendency of the handle to rattle. In addition, the spring 58 will force the blocks 52 toward the end of the column 48 to urge the hooks 14 tightly into engagement with the 90 brackets 12 and take up any play in the parts. When the handle is operated to release the catches, the springs 34 will aid in throwing back the catches 16.

In the species shown in Figures 8 to 13, 95 the connection 46' between the links 44' is made by the link 48'. The handle 70' has the squared end 68' which fits in the squared socket in the link 48' and is held thereon by means of the nut 86. The handle has secured thereto the disc 84 having the cut-out segment 86. The cut-out segment 86 cooperates with a finger 82' on a reinforcing member 74' secured to the inside of the hood 2 by means of the rivets 88. The rivets 88 also hold in position the outer reinforcing member 76'. The reinforcing member 74' has the extending collar portion 90 which fits against the disc 84 and holds the disc and link 48' spaced from the hood 2.

The hook 16' is in the shape of a coil spring 92, the end 94 of which is secured in a slot 96 in the stud of pivot 28' journalled in the bracket 18'. The hook spring 92 is coiled about the pivot 28' and its free end 14 forms the hook which engages under the bracket 12. The spring 92 is coiled under tension and is held from uncoiling or expanding by means of the bent end 96 of a lever 98 rigidly mounted on the pivot 28' 110 by means of a squared connection at 100 and the peened-over portion 102. The bracket 18' has a cylindrical extension 104 for the reception of the pivot 28' which has a flange 106 to form a head and which abuts against the 125 end of the extension 104. A coil spring 34' is wound about the extension and has its end 36' hooked into a slot 105 in the flange 106 while its opposite end 38 engages the bracket 18'. The function of the spring 34' is the 130

same as that of the spring 34 in the species of Figures 1, 2 and 4.

The operation of the structure of Figures 8 to 13, inclusive, is substantially the same as that of Figures 1 to 7, inclusive. The operation of the handle 70' will throw the links from the full line position in Figure 10 to the dotted line position. The links 44' will operate the levers 98 to cause the bent end 96 to move the hooks 16' from underneath the brackets 12. One of the intermediary positions of the hook 16' is shown in the dotted outlines 16'' in Figure 8. The continued movement of the link 44 will finally 15 throw the hook 16' to a position where it will clear the bracket 12.

The dotted line position 16a in Figure 8 shows the position which the spring hook 16' would occupy if the bracket 12 were not 20 interposed. The bent end 96 of the lever 98 is in the full line position (Figure 8) when the hood is in locked or latched position. The spring 92, 16' will take up any play or looseness in the mechanism and eliminates the necessity for the spring 58 in Figure 1.

In the species of Figures 14 to 17, inclusive, the invention is shown as applied to individual handles for each latch. The handles 70'' are journally mounted in the hood 2 by means of the reinforcing member 74'' secured to the hood by means of the rivets 88. A stud 108 is secured in an opening in the handle 70'' by means of the squared connection 110 and the peened-over portion 112. The stud 108 is journalled in the reinforcing member 74'' and secured to the other end 35 of an arm 114 by means of the nut 116.

The reinforcing member 74'' has formed 40 thereon a bracket portion 18'' which has formed thereon the cylindrical extension 104' in which there is journally mounted the pivot 28''. The pivot has an enlarged head 106' and a shank 118 which is slotted at 120 45 to receive the end of a coil spring 122 which has an end 124 which forms the hook which engages under the bracket 12. The spring is wound under tension similarly to the spring of the species of Figures 8 and 9 and 50 is prevented from uncoiling by means of the bent end 96 on a lever 98' rigidly mounted on the pivot 28'' by means of a squared connection 100' and peened-over portion 102'. The lever 98' has the cam slot 126 at its 55 opposite end and in the cam slot 126 there is received the pin 128 rigidly secured to the end of the arm 114.

The arm 144 has the shoulders 130 which strike against a bent-up tongue 132 formed 60 from the reinforcing member 74''. The purpose of the shoulders 130 and tongue 132 is to limit the throw of the handle 70''.

A spring 34'' is provided which has the same function as the spring 34'' in Figure 9. 65 The operation of the structure of Fig-

ures 14 to 17 is as follows: The full line position in Figure 16 shows the intermediary position of the parts between the latched and unlatched position. The dotted line position shows the locked or latched position of the parts. If it is desired to unlock the hood, the handle 70'' is rotated to swing the arm 114 clockwise (Figure 16) to cause the pin 128 in the slot 126 to swing the arm 98' to the right. This will cause the angle end 96 to engage the hook end 124 to swing it from the dotted line position through the full line position and to a position where it will be free of the catch 12. By moving the second handle 70'', the second hook will be disengaged and the hood may now be raised. The springs 122 and 34'' will prevent the parts from rattling and will always insure an easy and noiseless movement of the parts.

I claim:

1. In a hood latching means, a plurality of links having overlapping ends and extending away from each other inside the hood, a resilient connection between said overlapping ends comprising a hollow member, a spring in said member, blocks slidable in said member and urged apart by the spring, said ends secured to said blocks, and a handle to move said member to operate said links.

2. In a hood latching means, a plurality of links having overlapping ends and extending away from each other inside the hood, means interconnecting said ends, said interconnecting means including a resilient element to allow relative movement between said connection and said ends, and a handle connected to said interconnecting means to operate said links.

3. In a hood latching means, a plurality of links having overlapping ends and extending away from each other, a link operating member, means to which said ends are pivotally connected, said last-named means retained by said member and movable relative thereto, and a handle connected to said member.

In testimony whereof I affix my signature.

STEPHEN DE ORLOW.
